H. Souder.

Washing Machine

Patented Ant. 21, 1836.

No. 10

U.S. April 21, 1836 85.

Henry Souder, Lancaster Co. Pa.

Setters' Patent.

The schedule referred to in these Letters Patent and making part of the same containing a description in the words of the said Henry Souder, himself of his improvement in the Washing Machine."

Be it known that I, Henry Souder, of Lancaster, in the State of Pennsylvania, have invented a new and useful improvement in the manner of washing clothes, called "Setters' Washing Machine," and that the following is a full and exact description of the construction and operation of the said machine as invented by me.

The vessel is made of staves in the form of a barrel, slightly bulged two feet in length and twenty two inches in diameter, having a gudgeon forty five on the outside of each end on which it stands, with a chain or one of the gudgeons for the purpose of hoisting. Within are three horizontal bars called the battens of wood and in half inches in breadth and three feet long, and in thickness joined together and placed from each other, with one of their edges against the side and bounded on the other edge.

Twelve balls, made of hair, being made of three different sizes, five of four inches in diameter, five of three inches and five of two inches diameter or thereabouts are fastened to the vessel with the staves. An opening is made in one side of the vessel to admit the pieces intended to be cleaned, with a leather washing bottom and made tapering so as to close the opening when any operation is performed. The vessel is placed on a

bridge

RETURN

proper frame or stand, on which it is turned by means of the crank. This revolution of the vessel causes the balls to mingle and work in among the clothes and this produces the effect desired. One of the particular advantages of this vessel is, that from its closeness the steam is confined and the water kept to its proper degree of heat during the operation.

The inventor is not confined to the particular size above mentioned of the vessel, balls, or number and dimensions of the balls.
